UNITED STATES PATENT OFFICE.

CHARLES L. ELLIOTT, OF DETROIT, MICHIGAN.

INTERNAL-COMBUSTION ENGINE.

1,107,274.

Specification of Letters Patent. Patented Aug. 18, 1914.

Application filed January 24, 1913. Serial No. 743,894.

To all whom it may concern:

Be it known that I, CHARLES L. ELLIOTT, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art 10 to which it pertains to make and use the same, reference being had to the accompanying drawings, which form a part of this specification.

My invention relates to internal combustion engines and the object of my improvements is to provide an improved valve apparatus for such an engine. I accomplish this object in the device illustrated in the accompanying drawing, in which,

20 Figure 1, is an elevation mostly in section of the upper part of a cylinder of an internal combustion engine showing the valves of my invention adjusted thereto. Fig. 2, is an elevation of an engine with the apparatus embodying my invention adjusted thereto.

a is the cylinder of an internal combustion engine.

b is a passage extending laterally from the combustion chamber of the cylinder *a*.

c and *d* are ports through opposite walls of the passage *b* at the outer end thereof.

q and *r* are cylindrical openings formed in an extension from the wall of the cylinder *a*.

e and *f* are cylindrical valves fitting in the openings *r* and *q*. The ports *c* and *d* open through the wall of the openings *q* and *r* and diametrically opposite the ports *e* and *f*.

40 *d* are the ports *g* and *h* opening through the walls of said openings and extending over a greater angle of the circular cross section of said openings than do the ports *e* and *f*.

i and *j* are diametral passages or slots cut 45 through the cylindrical valves *e* and *f*. These slots are so arranged that their outer ends shall be in full register with the ports *g* and *h* when their inner ends commence to register with the ports *c* and *d*, and the inner ends of said slots shall pass by the open-

ings *c* and *d* so as to be out of register therewith, before the outer ends of said slots have passed the ports *g* and *h*.

s and *t* (Fig. 2) are sprocket wheels respectively upon the axes of the valves *e* 55 and *f*.

k is a sprocket chain extending around and engaging the sprocket wheels *s* and *t*.

m is a sprocket wheel secured to the valve *e* concentric with said valve. 60

o is the main shaft of the engine and *p* is a sprocket wheel thereon.

n is a sprocket chain extending around and engaging the sprocket wheels *m* and *p*.

The valves *e* and *f* have their axes extending transversely to the passage *b* and are located opposite each other and upon opposite sides of said passage. 65

x is the exhaust and *y*, is the intake passage. The ports *g* and *h* open into the passages *x* and *y*. 70

The operation of the above described device is as follows: When the engine is in motion, the turning of the shaft *o* rotates the valve *e* through the sprocket wheel *p*, 75 chain *n*, and sprocket wheel *m* and the rotation of the valve *e* causes a corresponding rotation of the valve *f* through the sprocket gearing *k*, *s*, *t*. The arrangement of the valves *e* and *f* should be such as to secure 80 the various cycles to the operation of the engine.

What I claim is:

1. In an engine, the combination of a cylinder provided with a single passage leading therefrom, two cylindrical valves having diametral slots therethrough, an intake passage adjacent to one of said valves and an exhaust passage adjacent to the other of said valves, said slots being adapted to form 85 communications between said passage and the adjacent intake and exhaust passage respectively, said valves being arranged opposite each other and upon opposite sides of the passage from the cylinder. 90

2. In an engine, the combination of a cylinder provided with a passage leading therefrom and with two cylindrical openings and having a port communicating between each 95 of said cylindrical openings and said pas- 100

sage, and a second port through the wall of each of said openings covering a greater arc of cross section of said wall than the corresponding first named port, a cylindrical valve in each of said openings having a slot therethrough the ends of said slot being arranged to register with said ports, so that their outer ends shall be fully open when the

inner ends are open at all, substantially as and for the purpose described. ¹⁰

[In testimony whereof, I sign this specification in the presence of two witnesses.

CHARLES L. ELLIOTT.

Witnesses:

AGNES M. HIPKINS,
ELLIOTT J. STODDARD.
